UNITED STATES PATENT OFFICE.

JOHN DRAHER AND ADOLPH J. KRIEGER, OF WATERBURY, CONNECTICUT.

SEPARABLE FASTENER.

Application filed December 24, 1925. Serial No. 77,442.

Fig. 1 is a plan view illustrating our improved separable fasteners.

Fig. 2 is a sectional view on the line 2—2 of Fig. 1.

5 Fig. 3 is an edge view of the eye-members.

Fig. 4 is an edge view of the hook-members.

Fig. 5 is a perspective view of one of the eye-members, detached.

10 Fig. 6 is a perspective view of one of the hook-members, detached.

Fig. 7 is a side view of a modified form of hook-member.

This invention relates to improvement in 15 separable fasteners, and particularly to that type which consists of complementary, interlocking members respectively secured on the edges of parts to be connected together with a slide having diverging channels, 20 through which the edges of the strips and interlocking members pass, and by which they are moved into and out of interlocking engagement. The object of the invention is to so form the members that less

25 metal is required, thus permitting the members to be arranged closer together to produce a cheaper and stronger construction, and the invention consists in the construction as hereinafter described and particularly recited in the claim.

In carrying out our invention, we employ eye-members 10, struck up from sheet-metal, with gripping-teeth 11, side flanges 12, and an extension 13 having a perforation 14. 35 The complementary members 15 are also formed from sheet-metal, with gripping-teeth 16, side flanges 17, and a forwardly-projecting finger 18 having a downwardly-turned end to form a hook 19 adapted to 40 enter the perforations 14 in the eye-members 10. These members are respectively secured to the edges of flexible strips 20 and 21 in

the usual manner, and the edges of these strips pass through a slide 22, having their diverging channels 23 in the usual manner, 45 and this slide is provided with a finger-piece 24, by which it may be conveniently moved.

As the slide is moved outward, the respective locking-members are brought together, 50 so that the hooks 19 enter the perforations 14, and the respective members are located so closely together that when engaged they cannot be removed, except by deflecting the strips, which is impossible, except through 55 the movement of the slide 22.

If desired, the hook-members may be provided with short studs 25, as shown in Fig. 7 of the drawings, these studs entering the lower end of the perforations 14 of the next 60 adjacent eye-member. This construction of interlocking members permits them to be readily struck up from sheet-metal, and permits the members to be arranged very closely together, so that, when engaged, a rigid 65 connection is made.

We claim:

A separable fastener, comprising two flexible strips, interlocking members respectively secured to the edges of said strips, said 70 interlocking members struck up from sheet-metal and formed with gripping-teeth and side flanges, the members on one side formed with projections having perforations, and the complementary members having projections with hooks to enter said perforations when the members are brought together, and a slide having diverging channels, through 75 which the edges of said strips and interlocking members extend.

In testimony whereof, we have signed this specification.

JOHN DRAHER.
ADOLPH J. KRIEGER.
